UNITED STATES PATENT OFFICE.

ERNEST U. DOWN, OF BOWLING GREEN, OHIO.

ADVERTISING-SIGN REPEATER.

Application filed October 10, 1921. Serial No. 506,549.

To all whom it may concern:

Be it known that I, ERNEST U. Down, a citizen of the United States, and a resident of Bowling Green, in the county of Wood 5 and State of Ohio, have made an invention appertaining to an Advertising-Sign Repeater; and I do hereby declare the following to be a full, clear, and exact description of the invention, such as will enable others skilled in the art to which it appertains to 10 make and use the same, reference being had to the accompanying drawings, and to the characters of reference marked thereon, which form a part of this specification.

15 My invention has for its object to provide a mechanism for causing repeated display of advertising signs by an exceedingly simple means. It provides means for dropping in succession and gradually rolling 20 up the signs behind those that have been dropped.

The invention may be contained in structures of different forms, and to illustrate a practical application of the invention I have 25 selected a structure containing the invention as an example of such structures, and shall describe it hereinafter. The structure selected is illustrated in the accompanying drawings.

30 Figure 1 of the drawings illustrates a front view of the mechanism, the front part of the casing having been removed. Fig. 2 illustrates an end view taken on the line 2—2 indicated in Fig. 1.

35 1 in the drawing is the casing that may be provided with a suitable lighting means, such as the lamp 2 located in the lower end of the casing and in position to show the signs as they are presented to view through 40 the glass 3, which is located in the front side of the casing.

The advertising signs are formed of flexible sheet material such as cloth backed paper, and the upper edges are connected 45 to rods 4. The ends of the rods are secured to rings 5. The rods 4, together with the rings 5 form a cylindrical rack on which the advertising signs 6 may be wound when the rack is rotated.

50 The rack is supported by means of the grooved wheels 7 and 8. The edges or peripheries of the rings 5 rest in the grooves of the wheels 7 and 8 and thus permit rotation of the rack. The rings 5 are each pro-

vided with an inwardly extending flange 9 having ratchet teeth 10, thus forming inwardly extending ratchets at each end of the rack. A motor 11 through a reducing gear and the shaft 12 rotates the arms 13 which are connected to the rod 15 located in the 60 rack. The rod slides over the teeth when the links 14 move in one direction by the operation of the arms 13 and engages the teeth 10 when the links 14 move in the opposite direction and move the rack 65 rotatively the distance between two consecutive teeth. In this way the flexible signs are rolled up on the rack. To permit the use of a large number of signs and to insure that each of the signs will be disclosed 70 in succession, means is provided for permitting each sign to fall after the preceding sign has been shown a definite period of time. A plurality of pairs of wheels, such as the rollers 16 and 17, are rotatably supported on rods 18 that are secured to the end walls of the casing, and are so positioned that they press against the side edges and corners of the flexible signs as they are carried around by the rack. The wheels 17 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840

I claim:

1. In a sign repeating device, a rack formed of a plurality of rods, and a pair of rings secured at the ends of the rods, flexible signs supported by the rods, grooved wheels for rotatively supporting each of the rings the rings having inwardly extending ratchets, a bar located in the rings for en-

gaging the teeth of the ratchet, a rotatable arm connected to the bar for producing reciprocatory movements in the bar for moving the rack step by step to display the 5 signs and wind the signs on the rack.

2. In a sign repeating device, a pair of rings, rods connected to the rings at the

ends of the rods, flexible signs connected to the rods, grooved wheels for supporting each of the rings, means for causing step by 10 step movements of the rings.

In testimony whereof, I have hereunto signed my name to this specification.

ERNEST U. DOWN.
